Des. 210,381
Patented Mar. 5, 1968

210,381

GRAPHIC RECORDER

Anthony P. H. Chan, Palo Alto, Calif., assignor to
Varian Associates, Palo Alto, Calif., a corporation
of California

Filed Aug. 14, 1967, Ser. No. 8,265

Term of patent 14 years

(Cl. D26—14)

FIG.1

FIG.2

FIG. 3

FIG. 4

FIG. 5

FIG. 1 is a perspective view of a graphic recorder showing my new design;

FIG. 2 is a top plan view;

FIG. 3 is a side elevational view, the opposite side being substantially a mirror image;

FIG. 4 is a front elevational view; and

FIG. 5 is a back elevational view.

The dominant features of the design reside in the portions shown in full lines.

I claim:

The ornamental design for a graphic recorder, as shown and described.
